UNITED STATES PATENT OFFICE

168,926

PORTABLE CHANGEABLE ROAD SIGNAL

Endell D. Davis and Albert G. Britton,
Silver City, N. Mex.

Application October 13, 1952, Serial No. 21,820

Term of patent 14 years

(Cl. D72—1)

To all whom it may concern:

Be it known that we, Endell D. Davis and Albert G. Britton, citizens of the United States, residing at Silver City, in the county of Grant and State of New Mexico, have invented a new, original, and ornamental Design for a Portable Changeable Road Signal, of which the following is a specification, reference being had to the accompanying drawing, forming part thereof.

Figure 1 is a front perspective view of a portable changeable road signal in its open position, showing our new design;

Figure 2 is a rear perspective view thereof, and

Figure 3 is a perspective view of the same in a closed position.

The dominant features of our design are shown in solid lines.

We claim:

The ornamental design for a portable changeable road signal, as shown and described.

ENDELL D. DAVIS.

ALBERT G. BRITTON.
